Patent expires April 25, 1961

6 Claims. (Cl. 179—18)

1

This invention relates to new and useful improvements in control circuits for automatic hunting or selector switches and the like, such as are useful in telephone or other communication systems in which alternating current marker potential is applied to groups of marking wires.

According to one of the features of the invention the marking wires in such a selector switch are individually connected to marking contacts of one or more final selectors or similar apparatus, and further groups of marking wires are each connected through resistances, induction coils, rectifiers, or a combination of two or more of these elements, or combinations of such elements with condensers, to a common point. Each group of marking wires is connected at this common point with a group marking wire, and the group marking wires are in turn connected with marking contacts of one or more finder switches or similar apparatus. The same alternating current marker potential which is connected to an individual marker wire, serves as a test potential for finding the individual marker wire in the apparatus for individual selection, as well as for finding the group marking wire during the hunting operation of the selector switch.

An automatic or semi-automatic telephone system or a similar system may thus be provided with two-motion final selector switches, which may be used for many other purposes, e. g. trunk hunting, line identification, etc. According to the invention the subscribers' lines may for identification purposes, be marked by alternating current marker potentials, while other groups of marker wires are each connected via resistances, inductance coils, rectifiers, or a combination of two or more of these elements or with condensers, (all of which I intend to cover by the word "impedance"), to a common point at which this group of marking wires is connected to a group marking wire. These group marking wires are connected to marking contacts of group identification switches of identification circuits and the final selector is set for group selection from the identification circuit by a series of impulses, the number of which is automatically determined by the setting of the group identification switch. The setting of the group identification switch on the group marking wire as well as the hunting for the individual marking wire by the final selector takes place under the control of detector apparatus in the identification circuit which responds to alternating current.

It is well-known that condensers used to pre-

2

vent the passage of direct current over a marking wire, e.g. the c-wire of a selector would have an influence on other marking wires and cause the undesirable response of relays or other receiving apparatus connected to these wires. Such a condenser allows, of course, alternating current to pass to a detector.

The charging and discharging of such condensers when a change of potential takes place in the c-wires, would cause the detector to react. Moreover, an individual condenser is required for each line and, even at rather high frequencies, e. g. 1500 Hz/sec., a 0.3 mF condenser must be provided. The common point must be connected to a predetermined direct current potential to apply a bias to the contacts of the finder switch, which hunts for all common points to identify the group marking wires to which the alternating current to be detected is connected. All this makes the arrangement expensive.

In order to reduce the costs, a high frequency must be used. However, on account of the danger of mutual influence, the potential must be low and the detector very sensitive. This great sensitivity may cause an undesired response of the detector apparatus on account of the above-mentioned bias.

By using resistances of sufficiently high value, (e. g. 1500 ohm), according to the invention the charging and discharging of the condensers will be avoided and equal bias will be automatically applied to the contacts, because the resistances are permanently connected to the source of direct current potential. Furthermore, the frequency may be reduced and the alternating current potential increased, thus making possible the employment of a less sensitive detector apparatus. Disturbing influence by the bias is then avoided.

The space required for the apparatus is smaller when resistances are used and the cost is considerably lower than with prior systems.

The c-wires in accordance with the present embodiment are connected over twice 15,000 ohm, i.e. 30,000 ohm, so that only a very weak current flows, but this is insufficient to produce any influence from one line to the other.

The invention will be described as embodied in a telephone system which is diagrammatically illustrated in the drawing.

Only those parts of the system are shown, which are used in the line identification arrangement of a telephone exchange employing power driven rotary switches. The final selectors have ten levels of twenty subscribers' terminals, and are controlled by reverte impulses from a register

controller set by the calling line in accordance with the numerical designation of the called line.

For connection for which the identification of the calling subscriber is required, is first built up over the customary first and second line finders or other non-numerical switches, and then extended to an exchange which acts as a nodal point for toll connections in a given area, (hereinafter called "main exchange"). From this point, the connection is established over one or more selecting stages which are not shown. The identification may be initiated from the main exchange at any appropriate moment. The manner in which the identification starts at the main exchange will not be described because it forms no part of the invention, which has to do with the switching operations for determining the number of the calling subscriber.

The identification is performed by two control circuits; one attached to the second line finder and the other to the subscriber's line circuit. The first control circuit is the identification-calling circuit, of which parts are illustrated in the right lower part of the drawing. The other circuit is the identification-sending circuit, of which parts are shown schematically in the left lower part of the drawing.

When a call is initiated on a subscriber's line, a free identification-calling circuit is connected to the circuit of the second line finder which, in a manner not disclosed here, is marked by the calling line. Relay Cr responds and a calling tone of 450 cycles is connected to a path over the c-wire of the line circuit of the calling subscriber. The subscribers' lines are so arranged in the terminal banks of the first line finders, and the latter on the banks of the second line finders, that an equal distribution of the traffic is obtained.

A second line finder circuit cannot identify the numerical group to which the calling line belongs. The identification-sending circuit will, however, find the calling tone which was placed on the line to be identified. In exchanges, in which the number of lines is larger than the normal capacity of a finder switch, the identification-sending circuit cannot have direct access to all lines by means of a single switch. In such cases the tone is picked up in two steps by the identification-sending circuit.

The subscribers' lines are divided into groups and, a common tone wire is provided for each group. This wire is connected to the bank of a first switch. The number of terminals in this first switch is thus reduced to the number of common wires representing subscriber's line groups, and the first switch must first determine the group of subscribers' lines to which the line to be identified belongs. The second purpose of this switch is to indicate the particular switch to which this group of subscribers is connected, and then to find the individual line on whose c-wire the calling tone was placed.

The common points of the common tone wires, and which represent a certain number of individual c-wires, may be provided in different ways. The c-wires must, however, be so connected to the common points as to avoid interference between the c-wires when direct current switching operations are performed over them. For example, resistances of 15,000 ohms are connected between the individual c-wires and the common point. The interference between the c-wires is then practically non-existent owing to the high value of these resistances and to the fact that the common point is connected through a low re-

sistance to a point of the same potential as that to which the c-wires are individually connected, viz. the winding of transformer TT, which is connected to the same battery potential as the apparatus, (Cor. SM), connected to the c-wire.

In the construction illustrated, 20 c-wires are commoned over individual resistances. The 20 subscribers' lines thus multiplied belong to one level of the final selector. In an exchange of 10,000 lines there are, therefore, 500 such common points, which have to be hunted over by the tone wire finders of the first switching stage. Assuming that this finder ICF is a 100-point switch, the 500 common points are arranged in five levels thereof.

The hunting for the calling tone may be carried out in many different ways. Five levels of 100 terminals each can be hunted over consecutively by a tone detector circuit, like the one indicated in the left lower part of the drawing. Another way is to provide in the identification-sending circuit five tone detector circuits, i. e. one for each tone wire finder brush cooperating with a level of the finder bank. While more expensive, this arrangement insures a quicker operation.

The current path for the calling tone is as follows:

Current source for a calling tone of 450 cycles, 30 right front contact of relay Cr, retardation coil RC₁, condenser C₁, brush a and terminal of finder CCF, brush g and terminal of second line finder, brush c and terminal of first line finder, resistance of 15,000 ohms, primary and secondary 35 windings of transformer TT, terminal and brush a of finder ICF, winding of transformer IT₁, earth.

The purpose of the transformer TT is to step up the voltage of the calling tone and to eliminate interference between the multiplied c-wires.

40 When the indication is received from a calling circuit, the brushes of the ICF finders of each free sending circuit start to rotate. When the calling tone is encountered, the voltage of the control gap of a cold-cathode tube TV₁ is increased beyond the breakdown voltage, and the tube becomes ionized. This results in the operation of relay It₁, which opens the circuit of the power magnet, and the brushes of the switch ICF stop on the terminal to which the calling tone is 50 connected.

Each position of finder ICF represents five levels each of twenty lines, all belonging to the same group of final selectors. A second finder IFF, forming part of the identification-sending- 55 circuit now seizes a free final selector which has direct access to the c-wire of the calling subscriber. The trip spindle of the final selector is set in the usual manner to the level, which includes the line of the calling subscriber. This 60 setting is controlled by the brush of finder ICF on which the calling tone has been detected.

The brushes of the final selector start to rotate, while a tone detector circuit IT is connected to the c-brush. This tone detector circuit is composed of the same elements as the one (IT₁) which tests the common points. Whilst the final selector is hunting for the tone, the revertive impulses sent from this selector will advance a step-by-step switch UM, by which a record is 70 made of the number of terminals passed by the final selector brush before it reaches the calling tone. The well-known revertive impulse circuit comprises the relays Flr and Os_r and the interrupter contact of the brush carriage.

75 As soon as the calling tone is found, tube TV

strikes and relay *For* responds. The circuit may be traced from the 450 cycle source of CCF, second LF, first LF, final selector, IFF, and back contact of *Ssr*. The magnet *P* of the final, stops the brush carriage on the terminals of the calling line and the sending of the calling subscriber's number may start. Relay *Ssr* is energized over the front contact of *For*, and connects over its front contact and brush *a* of finder IFF the impulse sending circuit to the *c*-wire.

Relay *Isr* follows the impulses of an interrupter and the digits of the calling subscriber's number are sent out one after the other in the well-known manner.

The different digits of the subscriber's number are determined in the following manner:

In a 10,000 line exchange, the last four digits are variable. The thousands digit is indicated by the position of the finder ICF. The hundreds digit is a function of the positions of ICF and of the step-by-step switch UM. The latter indicates whether the brushes of the final selector are standing in the first or in the second half of the terminal bank. In other words, whether the hundreds digit is odd or even. The tens digit depends on the position of ICF and on the level on which the calling tone was found. Finally, the unit's digit is determined by the position of switch UM.

The sending frequency in the above-described example is 1,500 cycles. The filter composed of C_2 and RC_2 prevents the impulse receiving circuit responsive to the identification impulse sender from operation on the identification-calling tone frequency. The impulses representing the calling subscriber's number and sent by the identification-sender are received over transformer DT by a cold-cathode tube DV. Every time tube DV strikes it will energize relay *A* which will repeat the impulses to the main exchange or some other destination, as required. On the first impulse, relay *Cr* releases and disconnects the calling tone.

What is claimed is:

1. In a telephone system, a plurality of numerically designated lines, means including non-numerical and numerical switches for connecting calling lines with called lines, a set of multiple terminals in the numerical switches for each of said lines, said terminals being arranged in groups, a brush for each numerical switch cooperating with its terminals, a source of alternating current of predetermined frequency, means for connecting said source over an operated non-numerical switch to the calling line, a detector responsive to said source of alternating current, means for connecting said detector to a group of lines including the calling line, another detector responsive to said source of alternating current, means for connecting the last-mentioned detector with the brush of a numerical switch, means including the last-mentioned detector for operating said brush to select the terminals of the calling line, a device for producing impulses representing the designations of the lines, a source of A. C. of different frequency for said device, a receiver responsive to the last-mentioned frequency, and means for connecting said device with said receiver over said numerical and non-numerical switches.

2. In a telephone system, a plurality of numerically designated lines, means including non-numerical and numerical switches for connecting calling lines with called lines, a plurality of levels of multiple terminals in the numerical switches in which said lines terminate, brushes cooperating

with said terminals, a first, a second and a third switch, a source of alternating calling current of predetermined frequency, means for operating the first switch to connect said source with the calling line over said non-numerical switch, a connection to a common point from the terminals of a group of lines which are connected to one level of the numerical switch, a resistance in each connection, a detector responsive to said source of alternating current, means for operating the third switch to connect said detector with a common point to which the calling line is connected, another detector also responsive to said source of alternating current, means for operating the second switch to connect the last-mentioned detector with a brush, a counting device associated with the second switch, means for operating said counting device once for each set of terminals traversed by said brush towards the terminals of the calling line, means controlled by the last-mentioned detector for stopping said brush upon the terminals of the calling line, a device associated with the second switch for producing impulses representing the designations of the lines, a source of A. C. of different frequency for said device, a receiver responsive to the last-mentioned frequency associated with the first switch, and a circuit for connecting said device with said receiver including in series the second switch, the numerical and non-numerical switches, and the first switch.

3. In a telephone system, a plurality of numerically designated lines, non-numerical and final selector switches for connecting calling lines with called lines, a set of multiple terminals for each line in the final selector switches, brushes for the final selectors cooperating with the terminals, a first, a second and a third switch, means for operating the first switch to connect with the non-numerical switch, the second switch to connect with the final selector and the third switch to connect with a group of said lines, a source of alternating calling current of predetermined frequency connected with the first switch, a detector associated with the third switch and responsive to said source of alternating current, means controlled by the detector for stopping the third switch, another detector also responsive to said source of alternating current associated with the second switch, an operating magnet for said final selector controlled by the last-mentioned detector, a counting device associated with the second switch, means associated with the second switch for starting the brushes of said final selector to move over its terminals, means for operating said counting device once for each set of terminals traversed by the final selector brushes towards the terminals of the calling line, means controlled by the last-mentioned detector for stopping said final selector brushes upon the terminals of the calling line, a device associated with the second switch for producing impulses representing the designations of the lines, a source of A. C. of different frequency for said device, a receiver responsive to the last-mentioned frequency associated with the first switch, and a circuit for connecting said device with said receiver including in series the second switch, the final selector, a non-numerical switch, and the first switch.

4. In a telephone system, a plurality of exchanges, a plurality of numerically designated lines at the first exchange, means including groups of non-numerical switches in series and a group of numerically operated final selector

switches at the first exchange for connecting calling lines with called lines at the first exchange, a set of contacts in the first group of non-numerical switches and terminals in final selector switches to which said lines are multipled, contacts in a second group of non-numerical switches connected with switches in the first group, inter-office connections extending from the second group and the brushes of final selectors to the second exchange, groups of third, fourth and fifth non-numerical switches at the second exchange, the connections to the second group of switches being multipled to the third group and those to the final selectors being multipled to the fourth group of switches, a source of alternating calling current of predetermined frequency connected in multiple to the third group of switches and over an operated switch of the second and third groups to a terminal of the calling line connected to a switch of the first group, a connection from the terminals of a group of lines to a common point at the first exchange, a resistance in each connection, transformers at the second exchange having primary and secondary windings, a connection from each common point to the primary of a different transformer, multiple connections from the secondaries of said transformers to switches of the fifth group, a detector at each switch of the fifth group responsive to said source of alternating current, means controlled by a detector for stopping its associated switch when the switch connects with a transformer connected to said A. C. source, another detector also responsive to said source of alternating current associated with each switch of the fourth group, an operating magnet for said final selector controlled by the last-mentioned detector, a counting device associated with each switch of the fourth group, means for starting the brushes of said final selector to move over the terminals of its bank, means for operating said counting device once for each set of terminals traversed by the final selector brushes towards the terminals of the calling line, means controlled by the last-mentioned detector for stopping said final selector brushes on the terminals of the calling line, a device associated with the switches of the fourth group for producing impulses representing the designations of the lines at the first exchange, a source of A. C. of different frequency for said device, a receiver responsive to the last-mentioned frequency associated with each switch of the third group, and a circuit for connecting said device with said receiver including in series a switch of the fourth group, the final selector, and switches of the first, second and third groups.

5. In a telephone system, a plurality of exchanges, a plurality of numerically designated lines at the first exchange, means including groups of first and second line finder switches and final selector switches at the first exchange for connecting calling lines with called lines, a set of multiple terminals in the first line finder and final selector switches for each of said lines at the first exchange, the terminals in the final selectors being divided into a plurality of levels, brushes for the first line finders and the final selectors cooperating with the terminals in said switches, terminals in the second line finders connected with the brushes of the first line finders, inter-office connections extending from the brushes of the second line finders and final selectors to the second exchange, groups of third,

fourth and fifth finder switches at the second exchange, each having a bank of terminals and cooperating brushes, the terminals of each fifth finder being divided into a plurality of levels, with each of which a different brush of the fifth finder cooperates, and the connections to the brushes of the second line finders being multipled to the terminal banks of the third finders and those to the brushes of the final selectors being multipled to the terminal banks of the fourth finders, a source of alternating calling current of predetermined frequency connected in multiple to the brushes of the third finders and over an operated second and third finder switch in series to a terminal of the calling line engaged by the brushes of a first line finder switch, a connection from the terminals of a group of lines in the same level of the final selectors to a common point at the first exchange, a high resistance in each connection, a source of D. C. potential, electromagnets for each line at the first exchange connected from one pole of said D. C. potential to the last-mentioned connection, transformers at the second exchange, each having a primary winding connected to the same and a secondary winding connected to the opposite pole of said D. C. potential, a connection from each common point to the primary of a different transformer, multiple connections from the secondary of each transformer to the terminals in the same level of the fifth finder, a plurality of detectors, each responsive to said sources of alternating current, and each connected with a different brush of the fifth finder, means operative upon the initiating of a call at the first exchange to operate one of said fifth finders to connect said detectors with its terminals in succession, means controlled by a detector for stopping the fifth finder when its brushes connects said detector with a transformer secondary whose primary is connected with said A. C. source, another detector also responsive to said source of alternating current connected with the brushes of the fourth finder, an operating magnet for said final selector controlled by the last-mentioned detector, a counting device associated with the fourth finder, means associated with the fourth finder for starting the brushes of said final selector to move over the terminals of its bank, means for operating said counting device once for each set of terminals traversed by the final selector brushes towards the terminals of the calling line, means controlled by the last-mentioned detector for stopping said final selector brushes on the terminals of the calling line, a device associated with the fourth finder for producing impulses representing the designations of the lines at the first exchange, a source of A. C. of different frequency for said device, a receiver responsive to the last-mentioned frequency connected with the brushes of the third finder, and a circuit for connecting said device with said receiver including in series the brushes and terminals of the fourth finder, the final selector, and the first, second and third finders.

6. In a telephone system, a plurality of numerically designated lines arranged in groups, means including non-numerical and numerical switches for connecting calling lines with called lines, a set of multiple terminals for each line in a non-numerical and a numerical switch, a contact for each switch cooperating with its terminals, a source of A. C. having a predetermined charac-

teristic, means including said non-numerical switch for connecting said source with the calling lines, a first device responsive to said source, means for connecting said device to a group of lines including the calling line, a second device responsive to said source, means for connecting the second device with the contact of said numerical switch, means including the second device for controlling the operation of said contact to select the terminals of the calling line, means for producing impulses identifying the lines, a source of A. C. of different characteristics for the last-mentioned means and a receiver responsive thereto, and a circuit including said numerical and non-numerical switches for connecting the receiver with the last-mentioned impulse producing means.
